UNITED STATES PATENT OFFICE.

FRANK KLEPETKO, OF NEW YORK, N. Y.

TWYER-BUSHING.

No. 795,842.

Specification of Letters Patent.

Patented Aug. 1, 1905.

Application filed February 11, 1905. Serial No. 245,292.

To all whom it may concern:

Be it known that I, FRANK KLEPETKO, a citizen of the United States, residing at New York, in the county of New York and State of New York, have invented certain new and useful Improvements in Twyer-Bushings, of which the following is a full, clear, and exact description, reference being had to the accompanying drawings, forming a part hereof.

My invention has relation to improvements A twyer-bushing; and it consists in the novel construction of bushing more fully set forth in the specification and pointed out in the claims.

In the drawings, Figure 1 is a vertical transverse section of a water-jacket on line 1 1 of Fig. 2, showing my invention applied thereto. Fig. 2 is an elevation of one-half of a water-jacket broken above the twyers. Fig. 3 is a sectional detail of a twyer of a shallow jacket, showing my invention applied thereto. Fig. 4 is a similar view showing a modified form of bushing; and Fig. 5 is a similar sectional detail of an ordinary nipple-twyer, showing my invention applied thereto.

The object of my invention is to construct a bushing for insertion into a furnace-twyer to protect the walls of the twyer against injury by the punching-bar, the frequent use of the latter in the "barring" of the furnace often resulting in injury to the twyer-walls and joints thereof if left unprotected.

In providing a twyer with a bushing for the specific purpose here referred to the construction of said bushing should be such as to prevent the same from slipping inwardly or outwardly in punching the twyer. To this end I have devised a bushing which while specially applicable to twyers whose bounding-walls are formed or expanded from the inside and outside sheets of the water-jacket of which said twyers form a part, the said bushing is equally applicable to the prevailing style of ordinary nipple-twyers.

In detail the invention may be described as follows:

Referring to the drawings, and particularly to Figs. 1 to 3, inclusive, 1 represents the inside sheet, and 2 the outside sheet of the water-jacket. At points where it is desirable to locate a twyer the inside sheet is punched and flanged outwardly—that is, toward the outside sheet—there being thus formed an opening bounded by the inwardly-flaring nipple 3. Opposite the nipple 3 of the inside sheet the

outside sheet has punched and flanged inwardly therefrom an outwardly-flaring nipple 4 of compound sectional curvature, the opening of said nipple 4 receiving the adjacent end of the nipple 3 and forming a tight joint therewith, the edge of the metal of the nipple 3 being expanded subsequently against the outer face of the nipple 4, thereby forming an expanded ring or head 5, insuring a tight joint. For jackets of moderate depth the end or edge of the nipple 3 is passed through an opening formed in the original wall of the outside sheet, as shown in Fig. 3, the end of the nipple being expanded against the outer face of said outside sheet, as in the form shown in Figs. 1 and 2. The twyer herein described I do not claim; but the same is alluded to, since my improved bushing is specially applicable thereto. This bushing comprises in one of its forms a tubular ring 6, having an inner peripherally expanded or flanged end 6', the outer end of the ring being preferably screw-threaded and provided with an annular ring or head 7, which in Figs. 1 and 2 rests in the depression formed by the inward flanging of the nipple 4. In Fig. 3 a similar head 7' is screwed to the outer projecting end of the ring 6. The annular head 7 (7') when once attached to the ring 6 virtually forms a terminal flange which overlaps the opening of the twyer, thus preventing the slipping of the bushing inwardly. The inner enlargement or flange 6' prevents the bushing from slipping outwardly, so that during the barring operation there is absolutely no danger of displacement of the bushing from its position in the twyer. The part 7 (7') also protects the joint at the outer end of the nipple 3 against injury from the punching-bar during the barring operation.

The inner terminal peripheral enlargement, which in the foregoing types of bushing assumes the form of an expanded flange 6', may be in the form of an annular ring or head 8, screwed (or otherwise secured) to the inner end of the tubular ring 6, as shown in Fig. 4, the outer wall of said band 8 flaring so as to conform to the curvature of the base of the nipple 3.

As before stated, the present bushing, while specially applicable to the flanged form of twyer already described, may be used in the ordinary nipple-twyer, as shown in Fig. 5. In said figure, 9 represents the ordinary nipple-twyer. The form of bushing specially

applicable thereto is like that shown in Fig. 3, comprising a tubular ring 6, an inner flange 6', and an outer head 7.

While the term "head" is herein used to designate the parts 7 7' 8, the term "flange" might be equally as appropriate, especially where its specific formation or connection with the ring 6 might suggest therefor the latter designation. I do not, of course, wish to limit myself to the form or configuration of the head 7, nor to the flange or enlargement 6' 8. Neither do I wish to limit myself to the number of pieces of which the bushing as an entirety may be composed, for it is apparent that I may depart in a measure from the details here shown without in any wise affecting the nature or spirit of my invention. Neither do I wish to limit its application specially to twyers.

Having described my invention, what I claim is—

1. A twyer-bushing comprising a tubular ring having an inner terminal peripheral enlargement, and an outer terminal head adapted to span the opening of the twyer, substantially as set forth.

2. A twyer-bushing comprising a tubular ring having an inner terminal peripheral inwardly-flaring flange, and an outer terminal head adapted to span or overlap the opening of the twyer, substantially as set forth.

3. In combination with a water-jacket having an inside and an outside sheet and provided with a twyer having an inwardly-flaring nipple leading from the inside sheet and coupled to the outside sheet, a bushing composed of a tubular ring having an inner terminal peripheral enlargement following substantially the contour of the nipple, and an outer terminal head spanning the opening of the twyer, substantially as set forth.

4. In combination with a water-jacket having an inside and an outside sheet and pro-

vided with a twyer having an inwardly-flaring nipple leading from the inside sheet and coupled to the outside sheet, a bushing composed of a tubular ring having an inner terminal inwardly-flaring flanged portion conforming substantially to the curvature of the nipple, and an outer head spanning and overlapping the opening of the twyer, substantially as set forth.

5. A twyer-bushing comprising a tubular ring having an inner terminal enlarged peripheral flaring portion, and an outer head or flange, substantially as set forth.

6. A twyer-bushing comprising a tubular ring having an inner terminal flange flaring beyond the peripheral walls of the ring, and an outer terminal head or flange for overlapping the twyer-opening, substantially as set forth.

7. In combination with a water-jacket having an inside and an outside sheet, and provided with a twyer having an inwardly-flaring nipple leading from the inside sheet and coupled to the outside sheet, an annular ring or head located in front of and protecting the outer end of said nipple, and means for retaining said head in position, substantially as set forth.

8. In a water-jacket having an inside and an outside sheet, a nipple extending from the inside to the outside sheet, and a protecting ring or head carried in front of the outer end of the nipple, substantially as set forth.

9. In a water-jacket having an inside and an outside sheet, a nipple connecting the sheets, and a protecting-ring located in front of the joint formed between the nipple and outside sheet, substantially as set forth.

In testimony whereof I affix my signature in presence of two witnesses.

FRANK KLEPETKO.

J. W. McBRIDE.

Correction in Letters Patent No. 795,842.

It is hereby certified that in Letters Patent No. 795,842, granted August 1, 1905, upon the application of Frank Klepetko, of New York, N. Y., for an improvement in "Twyer-Bushings," an error appears requiring correction, as follows: Page 1 in heading, the patent number, "75,9842," should be 795,842; and that the said Letters Patent should be read with this correction therein that the same may conform to the record of the case in the Patent Office.

Signed and sealed this 3d day of April, A. D., 1906.

[SEAL.]

F. I. ALLEN,

Commissioner of Patents.
